UNITED STATES PATENT OFFICE.

ANDERS JOHAN ENGLUND, OF SPOKANE, WASHINGTON.

OVERHEAD RAILWAY.

Application filed January 11, 1924. Serial No. 685,711.

To all whom it may concern:

Be it known that I, ANDERS JOHAN ENGLUND, a citizen of Sweden, residing at Spokane, in Spokane County, and State of Washington, have invented certain new and useful Improvements in Overhead Railways, of which the following is a specification.

The present invention relates to improvements in overhead railways of the single rail type designed for industrial use and particularly applicable in logging operations for transporting logs over mountainous or hilly lands where the usual surface railways cannot be built.

The invention involves the utilization of a train of coupled trucks with suitable propelling mechanism, and each truck is equipped with a pair of tiltable, outwardly dumping carriers supported below the overhead rail or track. Novel combinations and arrangements of parts are provided for retaining the carriers in normal position and for releasing the carriers at the proper time, as well as for retaining the load on the carriers. Means are employed for shifting the single support for the pair of carriers to properly balance the load on the truck, and other features are provided whereby logs and other materials to be transported may be handled with facility during the necessary operations.

The invention consists in certain novel combinations and arrangements of parts as will be hereinafter more specifically set forth and claimed.

In the accompanying drawings one complete example of the physical embodiment of the invention is illustrated wherein the parts are combined and arranged in accordance with the best mode I have thus far devised for the practical application of the principles of my invention.

Figure 1 is a transverse sectional view of the railway structure showing a truck in cross section and a pair of carriers in end elevation.

Figure 2 is a top plan view illustrating portions of a pair of coupled trucks and the mechanism for laterally shifting the load of the carriers, for counterbalancing.

Figure 3 is a side elevation of the shifting mechanism of Figure 2.

Figure 4 is a side elevation of a portion

of the overhead railway with one truck and carrier thereon.

Figure 5 is a top plan view of the cross beam for supporting the dumping carriers at the longitudinal center of a truck and the operating mechanism for releasing the pair of carriers.

Figure 6 is an enlarged vertical sectional view of one of the L-shaped carriers and its supporting arm, together with locking and releasing means therefor.

Figure 7 is a perspective view of one of the locking devices for the carriers.

The single track of the overhead railway is composed of standard railroad rails as 1, properly supported on the tops of spaced posts or uprights 2, which posts are mortised in and supported from the cross ties 3 having lateral diagonal braces 4. At a suitable height these posts are provided with side guides or trackways 5, one at each side of the posts, which extend parallel with the single track rail 1.

In Figure 2 portions of a pair of trucks are indicated as A and B, which are coupled as by a link C, and these trucks are coupled and utilized in suitable numbers to form a train propelled by suitable power and adapted to transport logs as indicated in Figure 1. The logs (or other material to be transported) are carried by two or more trucks depending upon the length of the logs, and as the load carried is supported at a suitable position below the overhead track, the center of gravity of the loaded truck is brought to the required point to insure stabilizing of the train or series of coupled trucks while in transit.

The trucks are supported above the single track and each truck, which is rectangular in shape, is made up of a pair of longitudinally extending parallel bolsters 6, 6, preferably of channel iron, which are tied together with straps or tie plates 7, and the pair of grooved traction wheels 8 are journaled in bearings 9 therefor on the top of the truck. The wheels are spaced apart equidistant from the longitudinal center of the truck and are located between the side bolsters, to roll on the single track as shown.

At the longitudinal center of the truck is provided a transverse plate 10 riveted or bolted to the two side bolsters to provide a rigid brace and support a transversely ar-

ranged shaft 11 which is journaled in bearings 12 on the top of the center plate and over the bolsters. This shaft is journaled to oscillate in its bearings, and is also 5 adapted to be shifted laterally of the truck, the truck however remaining at all times in parallelism with the single rail and perpendicular thereto regardless of the location of the longitudinal plane of the rail.

10 The horizontally disposed shaft 11 is provided with a rigid or integral upright stud shaft or pedestal 13 formed with a shoulder 13', and on this pedestal and its shoulder a cross beam 14 is supported, a block 15 15 being indicated in dotted lines as forming a rigid member of the beam for engagement with the pedestal, and resting upon the shoulder 13'. The cross beam is thus directly supported above the truck on the pedestal, and a nut 16 on the threaded end 20 of the pedestal retains the beam in position. The beam projects equidistant at the sides of the truck a suitable distance and may be made up of metal shapes to insure 25 strength and rigidity. At the respective ends of the beam are affixed a pair of depending arms 18 and 19, preferably of angle irons or channel irons, which arms curve inwardly from the beam ends and then extend 30 straight and downwardly parallel with the vertical axis of the single rail. Vertical braces formed of metal plates 20 are bolted or riveted to the cross beams and to the respective supporting arms to insure rigidity 35 of the structure, and of course these members which constitute a supporting frame depending from but movable relatively to the truck, are counterbalanced as closely as may be, and are provided with 40 guide rollers 21.

45 For longitudinally shifting the shaft 11 together with this supporting frame transversely of the truck body to equalize the load at the sides of the rail and balance the carriers to be described, I employ the shifting mechanism best shown in Figures 2 and 3. A screw bar 22 disposed transversely of the truck is journaled in a bearing 23 on one of the bolsters 6 and provided 50 with a hand wheel 24 at the side of the truck. On the screw bar is carried a travelling, nonrotatable nut 25 operatively connected with a shifting lever 26 which is pivoted at 27 on the truck. At the end of 55 the shifting lever a transversely extending link 28 is pivoted which link carries a fork 29 operatively connected with the shaft 11 at one end. It will readily be apparent that by turning the hand wheel in desired direction the shaft may be shifted longitudinally in its bearings, as indicated by dotted lines, which movement results in a lateral shifting of the supporting frame with relation to the truck. In some instances 60 the wheels 24 may be removed and

replaced by sprocket wheels and these wheels on succeeding trucks will be connected by chains in order that two or more supporting frames may be shifted simultaneously with relation to their trucks. 70

The supporting frame of the truck carries a pair of opposed carriers 30 and 31, which may be outwardly and downwardly tilted for dumping the load. These carriers are of L-shape and preferably of channel iron construction, each having a horizontally disposed load-bearing arm 32 projecting outwardly from the railway center, and the vertical portions of these carriers when they are in carrying position embrace 75 the supporting arms 18 and 19 as shown.

At the lower ends of the supporting arms 18 and 19 hinges 33 are provided for the L-shaped carriers to permit tilting of the carriers when the load is to be dumped. The 80 L-shaped carriers are locked to the supporting arms by a latch device or turn button 34 in connection with a slot 35 in the upright portion of the carriers. A supporting bracket 36 is provided in the supporting arm for the shank 37 of the button, and an angular lever 38 on the shank located at the inner side of the supporting arm is utilized to turn the shank and button in manner well understood to lock or unlock 95 the carrier and its supporting arm.

In addition to these devices for locking the carriers in normal position flexible braces or cables 39 are employed, one for each carrier. These braces are permanently 100 anchored as at 40 at the opposite ends of the cross beam 14 and the free ends of the cables are formed with loops or eyes 41 adapted to be engaged with the respective hooks 42, one of which is pivoted as at 43 105 at the outer end of each of the load-bearing arms 32 of the carriers. In addition to supporting the load bearing arms and relieving the strain on the carrier locks, these braces or cables retain the load on the 110 carriers as indicated in Figure 1, and prevent displacement of the logs.

When the carrier is to be tilted, after 115 unlocking, and the load is to be dumped, the hooks 42 are turned to permit disengagement therefrom of the cable loops 41 by the following release mechanism. A short length cable 44 is connected to the hook member 42 at a point in the required angular relation to the point of attachment of 120 the loop, which cable extends throughout the length of the load bearing arm 32 and is connected to a pivoted plate 45 which may oscillate on its pivot 46 in the carrier. A longer, upright cable 47 is attached to the 125 pivoted plate, (which plate performs the function of a bell crank lever) at a suitable point and extends upwardly and is pivotally connected with a lever arm 48 which is pivoted at 49 on an upright brace 20. As 130

seen in Figure 1 the two lever arms 48 are located at the sides of the vertical center of the railway, and the free ends of these arms, when the carriers are in normal position, project up to the top of the cross beam and at one side thereof. On the top of the cross beam is a latch 50 pivoted at 51 and extending parallel with the beam and transversely of the truck. The latch 10 is fashioned with a pair of detents 52, which as shown in Figure 5 project laterally from the beam in position to be engaged at their undersides by the free ends of the lever arms 48. It will be apparent that the load 15 of the carrier supported through the instrumentality of the hook 42 will hold the releasing cables under strain and this strain will hold the free ends of the lever arms up against the detents of the latch. A pull 20 on the releasing cord 53 will withdraw the latch, and the weight of the load of the carrier, when the latter is unlocked, now falls on the released hook 42 which is swung on its pivot 43 allowing the loop 41 to be 25 disengaged therefrom. The carrier is now released from the supporting cable and may tilt under the weight of the load to dump the latter. The latch 50 may be notched as at 54 to permit its movement with relation to the threaded end 17 of the pedestal 30 13, as seen in Figure 5.

The carriers may be loaded in any usual manner after they have been locked and are retained in position by the supporting cables 39, and the train of trucks may be propelled on the track by any suitable power.

Having thus fully described my invention, what I claim as new and desire to secure by Letters Patent is—

1. The combination with a railway truck, of a transversely arranged supporting member thereon, means on the truck whereby said member is permitted to swing in the direction of travel with relation to the truck, laterally disposed carriers supported from said member, and means for shifting said member transversely of the truck for counterbalancing the weight of the carriers.

2. The combination with a truck having a transverse shaft journaled thereon and means for shifting said shaft on its longitudinal axis, a pedestal fixed to said shaft, a transverse beam supported on the pedestal, supporting arms depending from said beam, and laterally arranged carriers supported from said arms.

3. The combination with an overhead railway truck of a transversely arranged supporting member thereon and means whereby said member may swing in the direction

of travel of the truck, laterally disposed depending arms carried by said member, and outwardly tilttable carriers pivotally supported in said arms. 65

4. The combination with a railway truck of a transversely arranged beam supported to swing thereabove in the direction of travel, laterally disposed rigid arms depending from said beam, outwardly tilttable carriers supported on said arms, a cable anchored to said beam for each carrier, means for attaching said cables to the carriers, and detaching means for said cables. 70

5. The combination with a railway truck 75 of a transversely extending beam supported on said truck, laterally disposed rigid arms depending from said beam at opposite sides of the truck, outwardly tilttable carriers pivotally supported on said arms, a cable 80 anchored on the beam at each side of the truck, said cables having a loop at their free ends, a pivoted hook on each carrier for said loops, and means for actuating said hooks to detach said cables. 85

6. The combination with a railway truck of a transversely extending beam supported thereon, a lateral arm depending from said beam, an L-shaped carrier pivoted in said arm, means for locking said carrier to said 90 arm, a cable having a looped end and anchored to said beam, a pivoted hook on the carrier for said looped end, a lever arm pivoted on said lateral arm and a flexible connection between said lever arm and hook, 95 and a releasing latch pivoted on said beam for retaining said lever arm in normal position.

7. The combination with a truck having a transverse shaft journaled thereon, a screw 100 bar journaled parallel with said shaft and a non-rotatable traveling nut on said bar, a pivoted lever arm connected with said nut, a shifting link pivotally connected with said arm and a forked member carried by said 105 link and engaging said shaft, a pedestal fixed to the shaft, a transverse beam supported on said pedestal, supporting arms depending from said beam, and laterally arranged carriers supported from said arms. 110

8. The combination with an overhead railway truck, of a transversely arranged supporting member thereon and means whereby said member may swing in the direction of travel of the truck, laterally disposed 115 arms depending from said member, outwardly tilttable carriers pivotally supported in said arms, and means for shifting said member transversely of the truck for counterbalancing the load of the carriers. 120

In testimony whereof I affix my signature.
ANDERS JOHAN ENGLUND.
